UNITED STATES PATENT OFFICE

172,919

DRAWER PULL

Earl M. Borchers, Rockford, Ill., assignor to
American Cabinet Hardware Corporation,
Rockford, Illinois, Rockford, Ill., a corporation
of Illinois

Application October 28, 1952, Serial No. 22,023

Term of patent 7 years

(Cl. D10—8)

To all whom it may concern:

Be it known that I, Earl M. Borchers, a citizen of the United States, residing at Rockford, in the county of Winnebago and State of Illinois, have invented a new, original, and ornamental Design for a Drawer Pull, of which the following is a specification, reference being had to the accompanying drawing, forming a part thereof.

In the accompanying drawing:

Figures 1 and 2 are respectively front and side elevational views of a drawer pull embodying my new design.

Fig. 3 is an end view.

Fig. 4 is a bottom view.

I claim:

The ornamental design for a drawer pull, substantially as shown.
